UNITED STATES PATENT OFFICE

2,476,479

TANK-WALL GRENADE MOUNTING

Dennis L. Brack, Fort Worth, Tex., assignor to
the United States of America as represented
by the Secretary of War

Application April 16, 1947, Serial No. 741,810

2 Claims. (Cl. 89—1)

1

This invention relates to improvements in combat vehicles and more particularly to a device for mounting grenades thereon whereby the combat vehicle is protected from close attack by unmounted enemy personnel.

Combat vehicles, such as tanks, have certain "blind spots" as a result of their construction and inclusion of armor plate. These blind spots are particularly disadvantageous when enemy personnel are unmounted and within extreme close range of the tank or even atop the tank itself. In such event the guns of the tank cannot be depressed sufficiently to bear upon targets of this nature. Furthermore, the necessity for determining the precise location of unmounted enemy personnel about the tank often leads to the ill-advised uncovering of a guarded portion of such tank thereby exposing the crew to enemy fire.

In an attempt to prevent attacks of such close nature, turrets have been installed in tanks to give a 360° field of vision. However, it takes a turret about 9 seconds to turn 180° from a dead stop, time enough for a successful attack to be completed even supposing that the turret machine gun could be brought to bear on the attacker at all. Moreover, a tank is helpless against simultaneous attack from opposite directions at short range. Obviously some method of discouraging or beating down such attacks is of great necessity.

Accordingly, it is an object of this invention to devise a method to prevent or subdue close-in attacks against an armored vehicle without requiring exposure of the crew to enemy fire.

It is a particular object of this invention to provide means for rotating an armed grenade from the interior of a tank to the exterior thereof where such grenade is detonated in a conventional manner.

The specific nature of the invention as well as other objects and advantages thereof will clearly appear from a description of a preferred embodiment as shown in the accompanying drawings in which:

Fig. 1 is a plan view of the ball of the invention with a grenade mounted therein;

Fig. 2 is a plan view of the ball mounted in the armor plate of a combat vehicle;

Fig. 3 is a top view of the ball mounted in the armor plate of a combat vehicle showing the two positions in which the ball may be secured;

Fig. 4 is a cross-sectional view taken along lines 4—4 in Fig. 2;

2

Fig. 5 is an exploded view showing how the handle is secured to the ball; and

Fig. 6 is a cross-sectional view taken along lines 6—6 of Fig. 3.

The invention essentially comprises a spherical ball 2 for carrying anti-personnel grenades 3 and adapted for mounting in the armor plate 4 of a combat vehicle. Oppositely disposed, hollowed-out recesses 5 are provided in ball 2 of sufficient depth to allow mounting of grenades 3 therein without such grenades projecting beyond the outer periphery of ball 2. Such requirement, of course, should leave a wall between recesses 5 equal to or greater than the thickness of the armor plate 4 of the combat vehicle as shown in Fig. 3, in order to insure adequate protection against the detonation of grenade 3. Recesses 5 are provided with floor surfaces 6 having a threaded stud 7 thereon suitable for mounting a grenade 3. Other means may of course be utilized for mounting the grenade and still be within the scope of this invention.

As shown in Fig. 5, ball 2 is provided with a handle 8 having an extension 9 by which such handle is threadably secured within ball 2. Handle 8 provides leverage for revolving ball 2 in the desired direction. Ball 2 is also provided with oppositely disposed mounting pins 10 in axial alignment with one another adapted for rotatable mounting within armor plate 4. When ball 2 has been inserted within a suitable cavity in armor plate 4 with pins 10 fitting within semi-circular recesses therein, a T-shaped insert 11 also provided with a semi-circular recess similar to that in armor plate 4, is bolted as at 12 to armor plate 4 over pins 10 thereby assuring free but non-tilting rotation of ball 2.

Spring brackets 13 are provided for securing handle 8 in either of two positions as shown in Fig. 3 and are secured to armor plate 4 as by screws 14. Such brackets are preferably so placed on each side of ball 2 as to surround the thinnest portion of handle 8.

Grenades 3 are mounted in ball 2 by means of the threaded studs 7 previously mentioned, preferably immediately prior to going into such action as may possibly warrant their use. When it is believed that enemy personnel are within close range of the armored vehicle or in actual contact therewith, the grenade 3 in the interior of the vehicle is armed by pulling the pin in the conventional manner. Then handle 8 is released from spring bracket 13 and ball 2 is revolved until handle 8 snaps into the other and opposite spring bracket 13. Thus grenade 3 is rotated to the

exterior of the vehicle where after the conventional few seconds' delay, such grenade detonates. The force of the explosion is obviously directed outwardly away from the armored vehicle and armor plate 4 thereof prevents any possible injury to the occupants. As grenade 3 is rotated as described, the other recess 5 is at the same time rotated into the interior of the vehicle whereupon another grenade may be mounted in such recess in a manner previously explained.

It should be also noted that the close fit of ball 2 with the surrounding sections of the armor-plated walls serves to prevent any enemy from interfering with the rotation of ball 2 by a bayonet blade for example. Moreover, ball 2 is preferably constructed of material having the same armored characteristics as the armor plate 4 of the combat vehicle so there will be no weakening in the protecting qualities of the armor-plated walls of the vehicle.

Thus there is here provided a simple but positive method of detonating grenades on the exterior of an armored vehicle to ward off close-in attacks by unmounted enemy personnel. The number of places from which such grenades may be fired is only limited by the size and type of the armored vehicle.

An embodiment of the invention having thus been described, it is understood that the invention is not intended to be limited to the exact details of such embodiment but may include such modifications and changes as come within the scope of the appended claims.

I claim:

1. In combination with a combat vehicle having armored walls, a metal ball rotatably mounted in an armored wall of said vehicle, said ball having oppositely disposed hollowed-out recesses for receiving a grenade, said recesses having each a stud mounted therein for mounting an explosive grenade, a handle secured to said ball substantially midway between said recesses and disposed

within said vehicle for oscillating said ball to alternately expose said recesses to the exterior of the vehicle, and means for securing said ball so that one of said recesses is disposed outside of said vehicle whereby an armed grenade can be mounted on said stud in the interior and discharged on the exterior of the vehicle.

2. In combination with a combat vehicle completely protected by armored walls, an armored door member mounted in an aperture in one of said walls to normally close said aperture, hinge means providing for substantially 180° rotation of said door member, mounting means accessible from within the vehicle for securing a grenade on one side of said door member and rotatable therewith, and manually operable means for rotating said door member so as to move said mounting means from the inside of the vehicle to the outside thereof, means for retaining said door in said last position, additional mounting means for a grenade on the opposite side of said door from said first means said last means being moved into the vehicle when the first mounting means is moved out and vice-versa, as the handle is oscillated back and forth to substantially 180°.
